UNITED STATES PATENT OFFICE.

MAX BUCH, OF DETROIT, MICHIGAN, ASSIGNOR TO HENRY E. EDWARDS, OF JACKSON, MICHIGAN.

TOP FOR VEHICLES AND THE LIKE.

1,285,921.

Specification of Letters Patent. Patented Nov. 26, 1918.

Application filed October 22, 1917. Serial No. 197,936.

To all whom it may concern:

Be it known that I, MAX BUCH, a subject of the Emperor of Germany, and resident of Detroit, Michigan, have invented certain new and useful Improvements in Tops for Vehicles and the like, of which the following is a specification.

My invention relates to improvements in folding tops for motor vehicles and the like and aims to provide an extremely simple and economical top which shall be selfsupporting during its folding and projecting movements, thus enabling it to be operated easily by a single individual and the folds 15 of the covering material to be properly arranged.

The invention also aims to provide a construction in which the liability of damage to the covering material in the closed position of the top will be reduced to a minimum.

With these and other objects in view, the invention includes the novel features of construction and arrangement and combination 25 of parts hereinafter described, my said invention being defined by the appended claims.

Several embodiments of my invention are illustrated in the accompanying drawings, 30 in which,

Figure 1 is a side elevation of a top.

Fig. 2 is a view of a modification; and Fig. 3 is a view of a five bow top.

In these drawings the top being shown 35 in side elevation, only the standard, bow arms, etc., on one side appear, but it will be understood that they are duplicated on the other side, only one side being shown for convenience.

Similarly in the following description and claims reference is made, for convenience, to the members on one side only.

In the drawings in which similar reference characters indicate the same or like 45 parts throughout the several views, and referring first to Fig. 1, the numeral 1 designates the body of the vehicle for which the top is adapted, and which is intended to be representative of any type of vehicle 50 or motor boat needing such a protective covering. The top covering material is indicated at 2 supported by the folding frame hereinafter described.

This comprises a main standard 3 designed 55 to have its lower end pivotally supported

in any suitable manner from the vehicle body, as indicated for example at 3^a, and designed to coöperate with one end or arm of the usual rear bow arm 4, which may be pivoted to the standard at 4^a. It will be 60 obvious, however, that if desired the rear bow arm might be pivoted to the body and the standard to the bow arm.

5 designates the outrigger bow or arm thereof which is supported by a pair of 65 links or members 6^x and 6^y, one having its front end connected to the outrigger bow arm or end in advance of the other and one pivotally connected to the standard above the point of connection of the other, 70 said links being pivotally connected together by a lock joint 6^a.

One of these (in the drawings the upper 6^y) is extended to carry or form the cover supporting bow 6^z. A forward cover supporting bow arm 5, and inclines rearwardly in relation thereto, being connected to the link 6^y by a distance piece or brace link 7^y, which causes the bow arm 7^x to be positively guided and positioned during the folding 80 and unfolding of the top.

In Fig. 2 I show a modification in which the main standard 3^c is pivoted to the rear bow arm instead of to the body iron. In this form a single link 6^c connects the outrigger bow arm 5 to the standard and supports a front supplemental bow arm 7^c to which latter is pivotally connected the forward end of a link or lever member 6^m which in turn is pivotally connected to the upper end of the standard and is extended in rear thereof to form a part of or carry the cover supporting bow 6^m.

In Fig. 3 I show a five bow top in which the extra bow 8 is carried directly by the 95 standard 3, but it is obvious that the standard in either of the other constructions may carry a rigid bow to convert the top into five bow tops.

While in the foregoing description I have 100 referred separately to the bows and bow arms, it will be understood that the bow arms may be made integral with the bows as in an all-steel top, or may be made as separate arms secured to the bows in any 105 suitable manner.

What I claim is:

1. In a folding top, a supporting standard, an outrigger bow arm, links supporting said outrigger bow arm, one link having its 110

rear end pivoted to said standard by a fixed pivot, and the other link also pivoted to said standard, by a fixed pivot, and having its rear end extended in rear of the standard 5 and positioned to form a cover supporting bow arm.

2. In a folding top, a supporting standard, an outrigger bow arm, a pair of links pivoted to said standard, one above the other and projecting forwardly therefrom, one of said links being pivotally connected to the rear end of the outrigger bow arm, and the other to a point adjacent said rear end, one of said links being extended in rear 10 of the standard, and its pivotal connection thereto being a fixed pivot, and a bow supported by said rearwardly extended link part.

3. In a folding top, a forwardly inclined main standard and a rearwardly inclined main bow arm, adapted to be pivotally supported from the body of a vehicle, a pair of links or members pivotally connected thereto, one above the other, and extending forwardly therefrom, and an outrigger bow arm supported from said links or members, one of said links or members having its connection with the standard by a fixed pivot and having a part extending in rear of its 20 pivot and forming a cover supporting bow arm.

4. In a folding top, a forwardly inclined main standard and a rearwardly inclined main bow arm adapted to be pivotally supported from the body of a vehicle, an outrigger bow arm, a pair of links or members pivotally supporting the end of said outrigger bow, and embodying a stop connection for limiting the upward swinging of the 30 links, said links or members being also piv-

otally connected to said standard one above the other, one of said links or members having a part extending beyond its pivot, and forming a cover supporting bow arm.

5. In a folding top, a standard, a rearwardly inclined main bow arm, an outrigger bow arm, a pair of links or members pivotally connected to said outrigger bow arm, one in advance of the other, and one at the rear end of said outrigger bow, one of said 45 links or members having a part extending beyond its pivot, and forming a cover supporting bow arm, and said pivot being a fixed pivot, a front auxiliary bow arm pivoted to said outrigger bow and a distance 50 link connecting said outrigger bow arm to one of said links.

6. In a folding top a main standard, an outrigger bow having its rear end pivotally supported from the said main standard by 55 means of links, an auxiliary front bow, one of the links being pivotally connected to the main standard by a fixed pivot and having its rear end extended in rear of said main standard and an inclined cover supporting bow directly carried by said extended part.

7. In a folding top, a supporting standard, an outrigger bow arm, a link pivotally connected to said standard and to said bow 65 arm by a lock joint, a second link pivotally connected with said standard and arranged to act as a brace for said outrigger bow arm when extended, one of said links having its rear end extended in rear of said standard 70 and positioned to form a cover supporting bow arm.

In testimony whereof, I affix my signature.

MAX BUCH.
